(57) **CLAIM**

The ornamental design for a faucet, as shown and described.

DESCRIPTION

FIG. 1 shows a front side perspective view of a faucet;

FIG. 2 shows a front view of the faucet which is at the right end based upon the orientation in FIG. 1;

FIG. 3 shows a first side view of the faucet which is opposite the side perspective view shown in FIG. 1;

FIG. 4 shows another side view of the faucet which is the front side view with respect to FIG. 1;

FIG. 5 shows a top side view of the faucet relative to the orientation in FIG. 1; and

FIG. 6 shows a perspective view of another embodiment of the invention wherein this embodiment does not have a hole in the handle; and,

FIG. 7 shows a top side view of the embodiment shown in FIG. 6 with all other sides for this embodiment being the same as shown in FIGS. 2-5.
